REFRIGERATING SYSTEM

Bruce De Haven Miller, Louisville, Ky., assignor
to The Girdler Corporation, Louisville, Ky., a
corporation of Delaware

Application June 21, 1938, Serial No. 214,884

17 Claims. (CL. 62—126)

This invention relates to that type of refrigerating system in which the refrigerating action results from the vaporization of a volatile refrigerant liquid and in which the resulting vapors are withdrawn, compressed, condensed and returned for revaporization.

In such systems it has been found that despite the use of oil traps and improved packing means for the compressor, a certain amount of lubricating oil used in the compressor ordinarily will find its way into the refrigerating system. Such oil being substantially non-volatile at the refrigerating temperature will, after a period of time, form films upon the heat transfer surface and in the piping and valves of the entire system. Such deposits on the heat transfer surface have an insulating effect which often materially reduces the efficiency of the heat transfer.

Where the evaporating liquid gasifies in direct contact with the heat exchange surface, the bubbles of gas often adhere to the surface or in traveling along the surface tend to space the volatile liquid from contact with portions of the heat transfer surface, and thereby tend to reduce the efficiency of the refrigerant liquid.

One object of the present invention is to provide an improved method in which the formation of insulating films of lubricating oil on the heat transfer surface is prevented, or in case such films be formed, they will be diluted and constantly and effectively removed from said surface whereby an improved heat transfer is obtained.

A further object of the invention is to provide an improved process in which gaseous films and bubbles generated by the vaporization of the volatile refrigerant are removed from or prevented from forming on the heat transfer surface.

A further object is to provide a method whereby the heat may be transferred from the heat exchange surface to the boiling refrigerant without the entire amount of the refrigerant to be boiled coming in contact with said surface and thereby reducing the amount of gaseous films or bubbles which would otherwise form on said surface.

A further object is to provide an improved method and apparatus whereby the velocity of the refrigerating medium along the heat transfer surface is appreciably increased and thereby any accumulation of films or bubbles on said surface is more effectively removed.

Other objects and advantages of the invention will be hereinafter pointed out or will be appar-

ent from a consideration of the accompanying drawing and the following description.

As one important feature of my invention I employ, in addition to the volatile refrigerant, a second liquid which is substantially non-volatile at the refrigerating temperature and which is mixed with and flows with the volatile refrigerant along the heat transfer surface. By means of such liquid a portion of the vaporization takes place in the resulting mixed liquid and heat is transferred from the heat transfer surface through portions of the liquid and much of the vaporization takes place out of direct contact with the heat transfer surface so that there is reduced liability of the bubbles forming on or traveling along said surface. By using a liquid which is a solvent for or miscible with lubricating oil, such oil is diluted or washed from the heat transfer surface and is prevented from accumulating on the latter. As a further feature the volatile refrigerant may be delivered in part at least through an injector nozzle which causes a rapid flow and continued circulation of the non-volatile constituent.

The accompanying drawing shows diagrammatically an arrangement of parts suitable for carrying out my improved method and constituting my improved apparatus, and it will be understood that the details of construction of the various parts may be modified within wide limits as such details constitute no novel portion of my invention. In the drawing Figure 1 is a diagrammatic drawing showing in vertical section one apparatus which may be employed and Figure 2 is a similar view showing an alternative arrangement of certain of the parts shown in Figure 1.

My invention may be used in a wide variety of processes and for the refrigerating of a wide variety of materials which may be in contact with or circulated over the separating wall presenting the heat exchange surface. Merely as an example, I have shown a unit which may be employed for the freezing of ice cream, chilling of lard, margarine, or other analogous material, or for treatment of other liquids, mixtures, or compounds. Such a unit is shown in the Bottoms and Wood Patent 2,013,025 and includes a cylinder 10 having an agitating, scraping, whipping, or beating element therein and rotated by a shaft 11 driven from an electric motor 12 or any other suitable source of power. Surrounding the cylinder is a jacket 13 through which the refrigerant liquid is circulated and in which the volatile constituent of the liquid may vaporize.

The refrigerant may be delivered through an inlet conduit 14 and the unvaporized portion of the liquid, together with the vapors, may be drawn off through an outlet conduit 15. The outer wall of the jacket 13 may be protected from heat losses by any suitable form of insulation 16. The material to be treated may be continuously delivered to one end of the cylinder 10 and continuously withdrawn from the opposite end, there being provided suitable conduits 17 and 18, one serving as the inlet and the other as the outlet.

In Figure 2 an alternative form of unit is illustrated which in most respects is very similar to that shown in Figure 1 except that it has its axis horizontally disposed instead of vertically disposed, and the refrigerant intake pipe 14 enters opposite to an end wall 19 of the cylinder or other chamber in which the material is to be treated. As illustrated in both Figures 1 and 2, the refrigerant jacket 13 is constructed to form a relatively thin annular space so that the refrigerating medium under pressure will move therethrough at relatively high velocity. This is preferable although not essential and the dimensions of the jacket as well as those of the cylinder 10 and the character of the agitating means may be varied through a comparatively wide scope.

In the system illustrated the volatile liquid refrigerant is delivered under pressure through a conduit 25 from the condenser of the compressor and may flow through a branch conduit 20 past a valve 27 to an accumulator 28. The valve 27 may be operatively connected to a float in the accumulator so that a predetermined level of the volatile refrigerant liquid may be maintained in the accumulator. The conduit 25 is provided with a second branch 30 having a control valve 29 leading to an injector nozzle 31 acting to withdraw liquid from the bottom of the accumulator 28 through a pipe 32 leading to the casing 33 around the nozzle and connected to the conduit 14 so that the high pressure refrigerant fluid escaping from the end of the nozzle 31 will withdraw liquid refrigerant from the accumulator and force it through the pipe 14 into the jacket 13.

The parts so far described may be similar to corresponding parts employed in other refrigerating systems.

As one important feature of my invention I use in connection with the volatile refrigerant a second liquid which is preferably miscible with the liquefied volatile refrigerant liquid; substantially non-volatile at the refrigerating temperature; and a solvent for lubricating oil. I have found that kerosene is suitable for this purpose, although other liquids might be employed.

The liquid should not become viscous at the low temperature of the evaporating chamber 13. Furthermore, the specific heat of the liquid should be such that when mixed with the primary refrigerant it will not reduce the efficiency of the refrigerating action to any appreciable extent. As the auxiliary liquid is substantially non-volatile at the temperatures existing in the system, it may be readily separated from the vapors resulting from the vaporization of the primary refrigerant liquid, and thus may be continuously circulated in the refrigerating cycle without passing back to the compressor. As the liquid performs its main function solely in the jacket, the recirculating portions of the system may be so designed that a relatively small amount of such liquid may be employed.

As illustrated in the drawing, the outlet 15 from the jacket 13 leads to a chamber 35 where the auxiliary liquid together with the unvaporized portion of the primary refrigerant may separate. The vapors may pass from this separating chamber 35 through a conduit 36 which joins a conduit 37 leading from the top of the accumulator and thence back to the compressor. This conduit may have a valve 38 beyond the point of junction of the conduits 36 and 37 whereby the back pressure in the refrigerating system may be controlled to thereby control the temperature in the jacket 13. The separating chamber 35 may have any suitable form of baffles or any type of eliminator to prevent drops of liquid from being carried out with the vapors leaving through the conduit 36. The bottom of the separating chamber 35 is connected by a conduit 39 leading to the casing 33 around the injector nozzle 31.

The system may be supplied with the proper quantity of the auxiliary liquid through a supply pipe 41 having a valve 42, and leading to the separating chamber 35 or to any other desired part of the system.

In starting the apparatus the valve 29 may be closed and refrigerant liquid will be delivered through the conduits 25 and 20 to the accumulator, and such liquid will mix with the auxiliary liquid to form a mixture which will seek its own level in the conduits 32 and 39, the refrigerating chamber, and the separating chamber 35. Upon opening the valve 29 the high pressure primary refrigerant will be delivered through the pipe 30 and nozzle 31, and will induce a flow of primary refrigerant through the pipe 32 and the auxiliary liquid through the pipe 39, and the resulting mixed liquid will flow into the jacket 13. Some vaporization of the primary refrigerant may take place in the conduit 14 to chill the liquid before entering the jacket, but the main evaporation will take place in the mixed liquid in the jacket 13, due to absorption of heat from the heat transfer surface of the cylinder 10. The unvaporized liquid, together with the vapors will pass out through the conduit 15 and will separate in the chamber 35, the liquid returning through the conduit 39 for recirculation, and the vapors going back to the compressor.

The back pressure on the system, and therefore, the temperature in the jacket 13, may be controlled manually or otherwise by the valve 38, and may also be controlled by a solenoid valve 43 in the conduit 36 and operated in accordance with the load on the motor. The refrigerating of the material to such an extent that it is too stiff in the cylinder 10, will result in an additional load on the motor 12, and this increased load may act through the electric connection 44 to close the valve 43, and expansion of liquid to gas will force the liquid back into the accumulator. This reduction in refrigerating action will cause the material to be hardened to a lesser extent, thereby relieving the load on the motor and permitting the valve 43 to reopen.

In my improved system the auxiliary liquid prevents the formation of lubricating oil films on the heat transfer surface of the cylinder 10 as well as in the pipes and valves; it permits a portion of the vaporization to take place in indirect rather than direct relationship to said surface; it reduces the volume of the primary refrigerant in respect to the capacity of the jacket 13; and due to its rapid flow, sweeps any bubbles or gas films from the heat transfer surface.

Due to the action of the injector nozzle 31 both the primary refrigerant and the auxiliary liquid are rapidly circulated and sufficient primary refrigerant enters the jacket 13 to accomplish the desired refrigerating action even though such primary refrigerant be diluted by the auxiliary liquid.

Even without the injector nozzle 31 there will be a flow of liquid, by reason of the difference in specific gravity of the liquid in the conduits 32 and 39 and the mixture of liquid and gas in the jacket 13, and this will cause a continued circulation of the auxiliary liquid upwardly in the jacket 13 and into the separator and a return of the non-vaporized portion through the conduit 39. The injector insures a more rapid circulation and adds refrigerant to the mixed liquid to supplement that supplied through the conduit 32 directly from the accumulator. The evaporation which may take place in the conduit 14 brings the auxiliary liquid to a very low temperature, so that such liquid by itself acts to abstract heat from the heat transfer surface as well as to conduct heat to portions of the primary refrigerant not in direct contact with said surface. Upon shutting down the apparatus, all of the primary refrigerant may be permitted to evaporate, leaving the auxiliary liquid in the system substantially free of primary refrigerant, and thus, when the valve 45 is opened the auxiliary liquid may drain through the pipe 46. It may be treated to remove therefrom the accumulated lubricating oil or other impurities, with very little loss of primary refrigerant. When purified it may be returned to the system through the inlet 41.

I have referred to kerosene as the auxiliary liquid, but indicated that other liquids might be used instead. For example, a certain percentage of water may be employed in the system in addition to the ammonia or whatever volatile refrigerant liquid may be used, and kerosene. In cases where lubricating oil does not present any problem, I may use water with the ammonia and without kerosene. The water under the pressures and temperatures existing in the system would not boil, and would serve equally as well as kerosene for scouring bubbles from the surface of the cylinder 10 and for conducting heat to portions of the primary refrigerant not directly in contact with the heat exchange surface. With 25% or more of ammonia dissolved in water as the auxiliary liquid, there will be no freezing of the water content, since such a percentage of aqueous ammonia will lower the freezing point of the solution to a lower temperature than is ordinarily required in processes of the character to which I have referred.

It will be understood that the drawing is diagrammatic, and that insulation will be employed around all portions of the system where heat may be absorbed from the atmosphere, and not merely around the jacket 13.

Having thus described my invention, what I claim as new and desire to secure by Letters Patent is:

1. The method of refrigerating a heat transfer surface which includes injecting a volatile refrigerating liquid into a stream of kerosene, circulating said kerosene over the surface to be refrigerated, vaporizing said refrigerating liquid in said stream, and separating the vapors from said stream.

2. The method of refrigerating a heat transfer surface which includes injecting a volatile re-

frigerating liquid into a stream of kerosene, circulating said kerosene over the surface to be refrigerated, vaporizing said refrigerating liquid in said stream, separating the vapors from said stream after leaving said surface, and returning the separated kerosene for recirculation.

3. In combination a refrigerating chamber, means for injecting a volatile liquid refrigerant into and thereby inducing flow of a relatively non-volatile liquid through said chamber, a separating chamber spaced from the refrigerating chamber and receiving the liquid and vapor from said refrigerating chamber, and means for returning said liquid from said separating chamber to said injecting means for recirculation through said refrigerating chamber.

4. In combination a refrigerating chamber, a separating chamber, an accumulator, an injector having a nozzle, means for delivering relatively non-volatile liquid from said separating chamber and a volatile refrigerating liquid from said accumulator to said injector, means for delivering refrigerant liquid under pressure to said nozzle to effect flow from said accumulator and said separator to said refrigerating chamber, means for delivering vapor and liquid from said refrigerating chamber to said separator, means for delivering separated vapor from said separator, and means for returning liquid from said separator to said injector.

5. In combination a refrigerating chamber, having an inlet and an outlet, a separator having an inlet connected to said outlet and having separate gas and liquid outlets, an accumulator, conduits from said accumulator and the liquid outlet of said separator to the inlet of said refrigerating chamber, an injector associated with said conduits, and means for delivering liquid refrigerant to said injector to effect delivery of liquid refrigerant from said accumulator and delivery of relatively non-volatile liquid from said separator to said refrigerating chamber.

6. A refrigerating apparatus including a refrigerating chamber, a source of supply of a volatile refrigerant liquid, a separator spaced from said refrigerating chamber, means for delivering volatile refrigerant liquid from said source of supply and relatively non-volatile liquid from said separator to said refrigerating chamber, means for injecting volatile refrigerant liquid under high pressure to enforce said delivery and the circulation through said refrigerating chamber, and means for delivering vapors of the refrigerating liquid from said separator.

7. In a refrigerating system, a heat exchange cylinder having a jacket, a separator connected to the upper portion of said jacket, an accumulator, a supply line for delivering liquid refrigerant under low pressure from said accumulator to the lower portion of said jacket, a supply line for delivering relatively non-volatile liquid from said separator to the lower portion of said jacket, an injector, means for delivering liquid refrigerant under high pressure to said injector to affect rapid circulation of said liquids through said jacket, and means for withdrawing vapors from said separator.

8. The method of refrigerating a heat transfer surface of an evaporator, which includes circulating a relatively non-volatile liquid in a closed cycle into, through and from said evaporator, evaporating a volatile refrigerating liquid in said first-mentioned liquid adjacent to said heat transfer surface, separating the resulting vapor from said first-mentioned liquid at another

point in the cycle after leaving the evaporator, and returning said first-mentioned liquid to said evaporator.

9. The method of refrigerating a heat transfer surface of an evaporator, which includes circulating a relatively non-volatile liquid in a closed cycle having said evaporator as a part thereof, mixing a volatile refrigerating liquid with said first-mentioned liquid in advance of contact with said surface, substantially completely separating said first-mentioned liquid from vapor resulting from vaporization of said refrigerating liquid adjacent to said surface and after the latter leaves said surface, and returning said non-volatile liquid to said evaporator.

10. The method of refrigerating a heat transfer surface, which includes circulating a substantially non-volatile liquid in a closed cycle over said surface, then through a separator and back to said surface, accelerating the flow of said liquid and refrigerating the latter by injecting a volatile refrigerant into the cycle in the direction of flow, and substantially completely separating the vapor of the refrigerant and said liquid in said separator.

11. In a refrigerating system, a heat exchange cylinder having a jacket, a separator connected to the upper portion of said jacket, an accumulator, a supply line for delivering liquid refrigerant under low pressure from said accumulator to the lower portion of said jacket, a supply line for delivering relatively non-volatile liquid from said separator to the lower portion of said jacket, an injector, means for delivering liquid refrigerant under high pressure to said injector to affect rapid circulation of said liquids through said jacket, means for delivering liquid refrigerant to said accumulator, means for delivering liquid and vapors from the upper end of said jacket to said separator, and means for withdrawing vapors from said separator and from said accumulator.

12. The method of refrigerating a heat transfer surface and freeing it from films and bubbles, which includes delivering a mixture of a substantially non-volatile liquid and a volatile refrigerating liquid at low pressure to an evaporator presenting said surface, flowing the mixture rapidly over said surface whereby at least a portion of said refrigerating liquid is gasified, removing the liquids and gases from said evaporator, separating the gases and liquids, reliquefying the gases and re-mixing the reliquefied gases with the substantially non-volatile liquid for re-delivery to said evaporator.

13. The method of refrigerating a heat transfer surface, which includes circulating a substantially non-volatile liquid under low pressure in a closed

cycle, including an evaporator presenting said surface, and a separator, at spaced points in the cycle, delivering a volatile refrigerant liquid to the cycle at a point in the latter where the first mentioned liquid flows from the separator to the evaporator, and removing vapors of the refrigerant liquid from the cycle at the separator.

14. The method of refrigerating a heat transfer surface, which includes circulating a substantially non-volatile liquid under low pressure in a closed cycle, including an evaporator presenting said surface, and a separator, at spaced points in the cycle, removing vapors of the refrigerant liquid from the cycle at the separator, reliquefying said vapors, and returning them to the cycle at a point in the latter where the first mentioned liquid flows from the separator to the evaporator.

15. The method of refrigerating a heat transfer surface, which includes circulating a substantially non-volatile liquid under low pressure in a closed cycle, including an evaporator presenting said surface, and a separator, at spaced points in the cycle, removing vapors of the refrigerant liquid from the cycle at the separator, reliquefying said vapors, and returning a portion thereof at low pressure to the cycle at a point in the latter where the first mentioned liquid flows from the separator to the evaporator, and returning another portion thereof at high pressure and injecting it into the cycle to increase the speed of flow in the cycle.

16. The method of refrigerating a heat transfer surface and removing films and bubbles therefrom, which includes entraining a relatively non-volatile liquid in a high velocity stream of volatile refrigerant, effecting vaporization of the volatile refrigerant to produce refrigeration, utilizing the action of said high velocity stream to produce a rapid flow of said non-volatile liquid over said surface in a manner to scour films and bubbles from the surface, substantially completely removing vapors from said non-volatile liquid and returning the liquid for reentrainment in said stream.

17. The method of refrigerating a heat transfer surface and removing films and bubbles therefrom, which includes providing a mixture of a volatile refrigerant and a relatively non-volatile liquid in which said refrigerant vaporizes to effect refrigerating action, producing relatively high velocity flow of said mixture over said surface in a manner to cool the surface and to remove films and bubbles from the surface by the scrubbing action of said liquid, separating the vapors from the liquid and returning the liquid for recirculation over said surface.

BRUCE DE HAVEN MILLER.
